T. F. CRARY

RAIN WATER CUT-OFF

Filed Feb. 19, 1924

Fig. 1.

UNITED STATES PATENT OFFICE.

THOMAS F. CRARY, OF MIDDLEPORT, OHIO.

RAIN-WATER CUT-OFF.

Application filed February 19, 1924. Serial No. 693,839.

To all whom it may concern:

Be it known that I, THOMAS F. CRARY, a citizen of the United States, residing at Middleport, in the county of Meigs and State of Ohio, have invented new and useful Rain-Water Cut-Offs, of which the following is a specification.

This invention relates to valve constructions especially designed for use in connection with drain pipes, whereby water passing through a drain pipe or rainspout may be directed to cisterns or sewers.

Another object of the invention is to provide a device of this character which will 15 guide the sliding valve member to a position to direct fluid to either the cistern or sewer pipe, the construction of the valve member being such as to insure against fluid entering the pipe leading to the cistern when the 20 valve member has been placed to direct fluid to the sewer which is in communication therewith.

A still further object of the invention is to provide means for locking the sliding 25 valve member against movement, after it has been positioned to accomplish a certain result.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed, may be made within the scope of what is claimed, without departing from the spirit of the invention.

Referring to the drawing:

Figure 1 is a side elevational view of a 40 device constructed in accordance with the invention, parts thereof being broken away to illustrate the interior thereof.

Figure 2 is a sectional view taken on line 2—2 of Figure 1.

Referring to the drawing in detail, the 45 reference character 5 designates the body portion of the device which includes a pipe section 6 and a pipe section 7, disposed laterally thereof.

The pipe section 6 may have communication 50 with a pipe 8 leading to a sewer, while the pipe 7 may have connection with a pipe 9 leading to a cistern, not shown, whereupon water passing through the body 5, may be directed to either pipe.

The pipes 6 and 7 have enlarged upper

ends and communicate with each other, the adjacent upper edges 10 of the pipes extending inwardly to provide inclined surfaces for the reception of the trough member 11. 60

This trough member is of a length so that the lower end thereof will extend into the pipe through which water is to be directed, while the upper end of the trough is formed with a laterally extended flange 12 designed 65 to rest on the upper surface of the body 5 to support the trough member against movement.

Due to this construction, it will be obvious 70 that the trough member 11 will be readily inserted in the upper end of the body 5, whereupon the same will be positioned at an oblique angle with respect to the upper edge of the body 5 to cause water to be directed laterally of the body portion. 75

It will be seen that the trough member 80 may be readily removed from a position as shown by Figure 1 of the drawing, and positioned in the opposite side of the body 5 to direct water to the pipe 6.

When the trough member has been positioned to discharge water into the pipes 6 or 7, it is obvious that ventilation of the cistern 85 communicating with the pipe may be maintained through the pipe, the upper ends of the pipes being open to the atmosphere as clearly shown by Figure 2 of the drawings.

At opposite sides of the enlarged upper 90 ends of the pipes 6 and 7 are depressions 13' which define walls or shoulders 15' to give the necessary clearance to the trough member 11 and at the same time assist in guiding the trough member to its active position.

A pipe 13 extends into the body portion 5 95 and is secured thereto as by means of rivets 14, the lower end of the pipe 13 being disposed in such position as to lie in proximity with the trough member 11 and direct water thereto. 100

Connected with the pipe 13 is a pipe 14 which may be the rainspout or other drain pipe from a roof, so that water will enter the body portion 5 direct. Keepers 15 are secured to the body portion 5 and have their lower ends extended inwardly where they are curved downwardly as at 16 to lie in the path of travel of the trough member 14 and guide the trough member to its proper position within the body portion 5. 110

The keepers 15 cooperate with the links 17 to provide means for the reception of a

suitable padlock whereby the trough member may be locked against movement after it has been set to direct water to one of the pipes 6 or 7.

5 At the lower ends of the off-set portions 15 are keeps 18 that accommodate arms 19 of the securing bracket 20 which is also formed with eyes 21 to receive suitable securing bolts not shown, so that the bracket member may be secured on a building construction and the arms 19 move through the off-set portions 18 to support the device.

10 I claim:—

15 In a device of the character described, a pair of pipe sections connected, and having a large upper end providing a body portion, a pipe disposed centrally of the body portion, for delivering fluid to the body por-

tion, keepers secured to the body portion and having inwardly extended portions lying 20 within the body portion, a trough member removably positioned within the body portion and adapted to lie under the pipe extending into the body portion, and said inwardly extended portions of the keepers 25 adapted to be engaged by the trough member to guide the trough member to its active position when the trough member is positioned in the body portion.

In testimony that I claim the foregoing as 30 my own, I have hereto affixed my signature in the presence of two witnesses.

THOMAS F. CRARY.

Witnesses:

H. J. HYSSELL,
ADA KING.
